A. H. SEARLE

GAME TABLE

Filed April 3, 1923

Inventor
ALLEN H. SEARLE,

By
P. Mallinckrodt.

Attorney

UNITED STATES PATENT OFFICE.

ALLEN H. SEARLE, OF SALT LAKE CITY, UTAH.

GAME TABLE.

Application filed April 3, 1923. Serial No. 629,614.

To all whom it may concern:

Be it known that I, ALLEN H. SEARLE, a citizen of the United States, and a resident of Salt Lake City, county of Salt Lake, and State of Utah, have invented a certain new and useful Game Table, of which the following, together with the accompanying drawing, constitutes a full, clear, and exact specification.

10 This invention relates to a game table, and its principal objects are to provide:

First. A table apparatus arranged for the playing of games in which balls and cues are used.

15 Second. A game structure so designed that it shall be possible to develop a high degree of skill on the part of persons playing the games.

Third. A game structure having efficiency 20 and durability.

Fourth. A game which may be sold at a reasonable price.

In attaining the objects outlined above, I provide a table structure, having, preferably, a plane surface, surrounded by an elevated rail or coping of a height sufficient to support a resilient bead or cushion extending along the perimeter of the coping, and at a height from the surface of the 25 table, such, that the balls used in playing the game, shall strike the bead or cushion at points somewhat above the center of the balls.

On the table surface within the coping, is 30 arranged a series of wickets or arches, each of which may have the shape of the letter U inverted. These wickets may be arranged in an endless variety of ways, depending upon the nature of the games to be played. 40 For example, the wickets may be arranged in number and location after the manner of the ordinary outdoor game of "croquet", as indicated in Fig. 1.

In order that the balls shall rebound 45 from the wickets it is desirable that the latter should have resilient properties, and to this end, the wickets may be formed of a core of comparatively non-resilient material enclosed in a resilient cover, such for 50 instance, as rubber tubing.

In playing the games, ordinary cues are provided, with which to impart motion to the balls. The balls are shunted back and

forth between the resilient bead and the wickets, through the wickets, or from wicket 55 to wicket, in such ways as may be suggested by the individual judgment of each player, and conforming to the rules of any particular game.

In the drawing,

Fig. 1 represents a plan of the table;

Fig. 2, a transverse section;

Fig. 3, a section, considerably enlarged, taken on the line 3—3, Fig. 1;

Fig. 4, a detail of the wickets enlarged to 60 the same scale as used in Fig. 3;

Fig. 5, a section on 5—5, Fig. 4;

Fig. 6, one of the balls, drawn to substantially the same scale as Figs. 3 and 4;

Fig. 7, an elevation of one of the cues 70 drawn to substantially the same scale as Figs. 1 and 2; and

Fig. 8, a fragmentary section, actual size, showing an alternate construction of the bead.

Referring to the drawing, 10 represents the top of a table, which may be made of wood, slate or other material, and may have a covering 12 of felt or other fabric. The top 10 may be joined at its perimeter, to 80 the side members 13 and the end members 14, these projecting above the plane of the table, to form the coping 15. A bead or cushion 16 may extend entirely around the inner perimeter of the coping.

The bead may be formed of a flat strip 17, of rubber, or other resilient material folded around a core 18, the two folds of the rubber strip being brought together as shown at 19 and 20, (Fig. 3). The two 90 portions 19 and 20 may be firmly held down on the coping by means of the clamping strip 21 secured by screws 24.

Another way of forming the bead (Fig. 8) 95 is to mold the resilient covering around the core 40, thus allowing the covering to be made a little heavier at the points where needed, for instance at 41 and 42.

The wickets 26 may be formed of a core 100 27 of metal or other material for strength, and be encased in a covering 28 of any resilient material, preferably rubber tubing, as shown in detail in Figs. 4 and 5. The lower extremities of the wicket cores 27, may be reduced in cross-section to form 105 shanks 29, as shown in Fig. 4, thus pro-

viding the shouldered portions 30 for bearing on washers 31, which latter may be countersunk in the upper surface of the top 10. The wickets may be threaded and drawn down tightly by means of the nuts 32, bearing against the washers 34.

The structure as described, may be supported upon legs 35, or if desired, the legs may be omitted, and the game structure be set upon any ordinary table of suitable size.

The cue 36, Fig. 7, may be tipped with leather at 37, in the usual manner. The balls 38 should preferably be true spheres, as nearly as possible, and may be made of lignum vitae, hard maple, or other substances.

As an example of the manner in which games for which this table is adapted, are played, I connect (Fig. 1) in broken lines 45, a succession of wickets to be passed through, so that the player may win in a game modeled after ordinary croquet, previously mentioned. Obviously, it is not possible to strike a ball from any one position, and have it follow the course indicated. However, by causing the ball to be shunted over the table plane along a series of connecting lines (a few of which are indicated by dots and dashes at 46) touching various points on the wickets and bead, the ball can, in a series of well planned "shots," be made to pass through the wickets in the order desired.

While for convenience, a specific embodiment of this invention is herein shown and described, it should be clearly understood that the detailed parts thereof, may, or may not, be shown in the preferred forms, and further, that the preferred forms may be varied from time to time as the development of the invention and the arts with which it is identified, progress.

To the skilled inquirer, therefore, that which is an essential and characteristic part of this invention, will be readily discernible from the claims in which its spirit is broadly generalized.

Having fully described my invention, what I claim is:

1. A game apparatus comprising a table structure having a plane surface, a coping projecting upwardly from the said surface, a resilient bead extending along the said coping, and a plurality of wickets having resilient properties, positioned in a predetermined arrangement on said table surface within the said coping, each wicket consisting of a core in an elastic jacket or skin.

2. A game apparatus comprising a table structure having a plane surface, a coping connected to the said table structure at the perimeter of the said surface, a resilient bead arranged longitudinally along the inside of the said coping, the said bead being spaced apart upwardly from the table surface, a plurality of wickets each having a non-resilient core encased in a resilient extended jacket, the said bead and wickets being arranged in predetermined mutual relation for shunting rolling bodies over the surface of the said table.

3. A game structure having a playing surface, a cushion extending along the perimeter of said surface, resilient wickets spaced apart from each other and from the said cushion within the said perimeter, bodies adapted to roll on the said surface, wickets having extended tubular jackets and means for imparting motion to said bodies.

4. A game table having a playing surface, a coping projecting upwardly therefrom, a resilient member protruding inwardly from said coping, and resilient wickets having tubular elastic skins arranged within the said coping.

5. A game table having a playing surface, a coping having a resilient portion projecting upwardly from said surface, and wickets having resilient portions, all said resilient portions being arranged in spaced relation to each other and consisting of tubular, U-shaped, elastic skins.

In testimony whereof, I sign my name hereto.

ALLEN H. SEARLE.
